EXPANDING TOOL

George D. Buck, St. Louis, Mo.

Application November 23, 1936, Serial No. 112,439

3 Claims. (Cl. 218—19)

My invention relates to expanding tools, and has for its principal object to produce such a tool that is simple in design and construction, and highly efficient in its operation. Another object is to produce such a tool so that access to difficult locations may be readily obtained and the operation of the tool be unaffected thereby.

Partition walls in buildings are usually of such construction, being formed of plaster board, tile, marble, or the like, that it is difficult to attach fittings thereto, such as soap dispensers, junction boxes, towel cabinets, and the like. In many such cases tubular expanding anchors are employed, the anchor passing through a perforation made in the wall, and afterwards the anchor is expanded, thereby providing a supporting member in said partition wall to which the device to be mounted on the wall may be secured, preferably by a screw or threaded bolt. Ordinarily a series of such anchors is employed, so that a secure support may be obtained. In the use of my device a tubular anchor is attached to said device and then passed through a hole made in the partition wall to receive it, and then my device is manipulated to expand the anchor, such expansion taking place on the inner side of said wall and the anchor being thereby securely held in fixed position. My tool is then detached from the expanded anchor and withdrawn, when said anchor may be utilized as the supporting member for the device to be mounted on said wall.

For purposes of illustration, I have shown in one of the views of the annexed drawings a junction box with one anchor in place, duly expanded, and another anchor in position with my tool applied thereto, ready to be expanded. By this method a device having a relatively thin attaching wall may be securely placed in position on a thin partition wall.

Fig. 1 is a side elevation of my expanding tool.

Fig. 2 is an enlarged side view of the head end of my expanding tool in section, taken on the line 2—2, Fig. 4.

Fig. 3 is a view, partly in section, taken on the line 3—3 of Fig. 2, looking in the direction of the arrows.

Fig. 4 is an enlarged, top plan view of the head of my expanding tool with some of the parts in dotted outline.

Fig. 5 is a view, partly in section, of a junction box placed against a partition wall with one tubular anchor in expanded condition to secure said junction box in position and one tubular anchor in unexpanded condition in position to

be expanded with my expanding tool, which is shown attached to said unexpanded anchor and ready for the expanding operation.

In the drawings the head 10 of my expanding tool is formed with a horizontal passageway 11 therethrough adjacent its upper end. Ears 12, projecting downwardly from the head 10, are provided with slots 13 and 14, through which slots project bolts 15 and 16, respectively. The bolts 15 and 16 pass through perforations in rounded projections 17 and 18 at the upper end of a movable handle 19. The bolt 16 serves as the pivotal support for the movable handle 19, and the slot 14 permits a sliding movement of said bolt 16 as the handle 19 is manipulated. The function of the bolt 15 will be hereinafter described.

To the inner portion of the head 10 is fixed a handle 20 secured to said head by a screw 21. A flat spring 22 is bent as at 23 and attached to the handle 19 by the screw bolt 24. The outer end of the spring 22 engages the handle 20, as clearly shown in Fig. 1. The purpose of the spring 22 is to normally keep the handles 19 and 20 in separated position.

In the passageway 11 there is mounted a bar 25 of rectangular shape in cross-section. This bar 25 has a longitudinal passageway 26 therethrough to receive a cylindrical rod 27. The rod 27 is provided with a circumferential groove 28 near one end thereof to receive two pins 29 entering said groove for the purpose of retaining the rod 27 securely in the passageway 26. The pins 29 are apertured at their outer ends to receive a yoke 30 passing through said apertures, said yoke 30 being loosely placed about the bar 25. Ratchet teeth 31 are provided on the lower face of the bar 25, said teeth being of saw-tooth construction. To one end of the rod 27 is affixed a knurled turning member 32 for the purpose of rotating said rod 27.

Screwed into the upper face of the bar 25 is a plug 33, which plug is positioned in a slot 34 provided in the outer wall of the head 10. The purpose of the plug 33 in the slot 34 is to limit the horizontal movement of the bar 25 in the head 10. Fixed in the front end of the passageway 11 in the head 10 is another bar 35, which has a longitudinal passageway 36 therethrough to receive the rod 27. The bar 35 preferably extends for a distance beyond the head 10, so that the outer face 37 of said bar 35 may be employed for the expanding operation hereafter to be described, particularly where my tool must operate efficiently in positions difficult of access.

The outer end of the rod 27 is screw-threaded as shown at 38. A yoke-shaped member 39 is mounted on the head 18 and provided with apertures to receive the bolt 15. The connecting web 40 of the yoke-shaped member 39 engages at one edge the teeth 31 on the bar 25. The yoke-shaped member 39 is held in engagement with the toothed face of the bar 25 by a spring 41, which spring is provided with arms 42 at its outer portion, said arms passing into perforations in the head 18 to secure said spring 41 in position and having legs abutting the edges of handle 28 as shown. This permits a rocking motion of the yoke-shaped member 39 against the action of the spring 41 when the handle 18 is manipulated for operating the bolt 15 and the yoke 39. It will be noted that the bolt 15 is adapted for horizontal movement in the head 18 by being mounted in the elongated slot 13. It will be seen in Fig. 2 that the inner end of the bar 25 contacts with the inner end of the bar 35, said bar 25 being at the limit of its inner movement as shown in Fig. 2.

In Fig. 5 I have illustrated the method of utilization of my expanding tool, in which A is the partition wall, B a junction box, and C a tubular anchor in expanded condition securing the upper portion of the junction box B to the partition wall A. It will be understood that perforations have been prepared in the junction box B and the partition wall A to receive the tubular anchor C. Near the lower portion of the junction box B is shown an unexpanded, tubular anchor with my expanding tool attached thereto. The tubular anchor is composed of an elongated body D having a headed end E. The other end of the expanded anchor C is reduced in diameter as at F, the reduced portion being internally screw-threaded to receive the screw-threaded end 38 of the rod 27. The expanding anchor C is provided with longitudinal slots G and a series of perforations H, so that when pressure is applied by my expanding tool said anchor will collapse and expand into the position shown at the upper portion of the view in Fig. 5.

In the operation of my device, the tubular anchor C is first threaded onto the rod 27 with the head E of said anchor impinging against the outer end of the bar 35. The tubular anchor is then passed through the apertures provided for its reception in the partition wall A and the fitting, such as the junction box B, at which time the parts of the expanding tool appear in the position illustrated in Fig. 5. The handles 19 and 28 are then grasped by the operator and the handle 19 manipulated to force said handle 19 inwardly toward the handle 28 against the action of the spring 22, which causes the projecting portion 18 to pivot about the bolt 15, thus tending to move upwardly the projection 17 carrying with it the bolt 15 which moves the yoke member 39 outwardly. The connecting web 40 of said yoke member 39, being engaged at one side with the teeth 31 on the bar 25, forces said bar outwardly, carrying with it the rod 27 and the threaded, reduced portion of the tubular anchor C which is engaged by the threaded end 38 of the rod 27.

As the outer end of the bar 35 rests against the outer portion of the head E of the tubular anchor C, the tubular anchor is held firmly in the position illustrated in Fig. 5. Continued movement of the handle 19 toward the handle 28 causes the tubular anchor C to collapse and expand outwardly, due to the slots G and the weak-

ened, apertured portions H, so that the anchor C can be expanded into the position illustrated in the top portion of the view in Fig. 5. The rod 27 has been rotated by the knurled member 22 to cause the engagement of the threaded end 38 of said rod to engage with the threaded, reduced portion of the tubular anchor C. When the tubular anchor C has been expanded to its desired extent, the rod 27 is detached from the tubular anchor by manipulation of the knurled member 22 to detach the threaded end 38 of the rod 27 from the threaded, reduced portion of the tubular anchor C.

In Fig. 5 the extended bar 35 is illustrated to show the applicability of my expanding tool to a different location, with the tool in completely operative condition.

I claim:

1. An expanding tool comprising a head, a slideable bar mounted in said head, said bar being provided with a longitudinal passageway, a rod mounted in said longitudinal passageway in said slideable bar and movable with said bar, another bar associated with said head and provided with a longitudinal passageway therein to receive said rod passing loosely through said last-named passageway, a toothed portion provided on said slideable bar, a member associated with said toothed portion and adapted to transmit movement to said slideable bar and rod, a fixed handle carried by said head, and a movable handle also carried by said head and associated with said member for moving said member to transmit movement to said slideable bar and rod, and connecting members for permitting said movable handle to move.

2. An expanding tool comprising a head, a slideable bar mounted in said head, said bar being provided with a longitudinal passageway, a rod secured in said passageway and adapted to rotate therein, a member abutting one end of said slideable bar and secured to said rod and through which rotary movement may be imparted to said rod, another bar mounted in said head and provided with a longitudinal passageway loosely receiving said rod, a toothed portion on said slideable bar, a member associated with said toothed portion, a movable handle carried by said head and secured to said member for moving said member, and a fixed handle also carried by said head and adapted to cooperate with said movable handle when movement is imparted to said movable handle.

3. An expansion tool comprising a head, a slideable bar mounted in said head, said slideable bar being provided with a longitudinal passageway, another bar also mounted in said head and extending outside said head, said other bar being provided with a longitudinal passageway in registration with the longitudinal passageway in said slideable bar, a rod mounted for rotary movement in the longitudinal passageways in said slideable bar and in said other bar and movable with said slideable bar, said rod projecting beyond the outer end of said other bar, a member mounted on said rod and secured to one end of said rod and through which rotary movement may be transmitted to said rod, teeth on one portion of said slideable bar, a member engaging said teeth, a handle mounted on said head and engaging said member to permit imparting sliding movement to said slideable bar, and another handle fixed to said head and co-operating with said first-named handle.
